US00D800840S

(12) **United States Design Patent** (10) **Patent No.:** **US D800,840 S**
(45) **Date of Patent:** **** Oct. 24, 2017**

(54) **PANEL CONNECTOR**

(71) Applicant: **Atomic Design Inc.**, Lititz, PA (US)

(72) Inventor: **Thomas McPhillips**, Manheim, PA (US)

(73) Assignee: **Atomic Design Inc.**, Lititz, PA (US)

(**) Term: **15 Years**

(21) Appl. No.: **29/530,799**

(22) Filed: **Jun. 19, 2015**

(51) LOC (10) Cl. **20-99**

(52) U.S. Cl.

USPC **D20/99**

(57) **CLAIM**

The ornamental design for a panel connector, as shown and described.

DESCRIPTION

FIG. 1 is a top, front and right side perspective view of a panel connector, showing the new design;

FIG. 2 is a top, rear, and left side perspective view thereof;

FIG. 3 is another top, rear, and left side perspective view thereof;

FIG. 4 is a top plan view thereof;

FIG. 5 is a bottom plan view thereof;

FIG. 6 is a rear elevation view thereof;

FIG. 7 is a front elevation view thereof;

FIG. 8 is a right side elevation view thereof;

FIG. 9 is a left side elevation view thereof;

FIG. 10 is a bottom, front and right side perspective view thereof; and,

FIG. 11 is a top, front and right side exploded perspective view thereof.

The broken lines shown in the Figures are included to show unclaimed subject matter only and form no part of the claimed design.

1 Claim, 10 Drawing Sheets
